SUPPORT CABINET FOR A SLIDE PROJECTOR

William C. Ralke, 641 N. Highland Ave., Los Angeles,
Calif. 90036, and Jack K. Duncan, 10436 San Jose
St., Southgate, Calif. 90280

Filed Oct. 11, 1966, Ser. No. 4,230.

Term of patent 14 years

(Cl. D61—1)

FIGURE 1 is a perspective view of a support cabinet for a slide projector showing our new design;

FIGURE 2 is a side elevational view of the cabinet showing the design;

FIGURE 3 is a side elevational view thereof opposite to the side shown in FIGURE 2;

FIGURE 4 is a front elevational view of the cabinet;

FIGURE 5 is a rear elevational view of the cabinet; and

FIGURE 6 is a top plan view of the cabinet.

The dominant features of the design reside in the portions shown in full lines.

We claim:

The ornamental design for a support cabinet for a slide projector, substantially as shown and described.
